COIN DISPENSING TRAY

Otis E. Hoffman, Charles J. Wallman, and Arnold R. Buchholz, Watertown, Wis., assignors to Brandt Automatic Cashier Company, Watertown, Wis., a corporation of Wisconsin

Filed Dec. 11, 1962, Ser. No. 243,802

4 Claims. (Cl. 232—65)

This invention relates to a coin dispensing tray, and particularly to a coin dispensing tray for attachment about the discharge of a coin dispensing machine, which tray has a bottom which is displaceable upon actuation by an operator to deposit into the operator's hand coins received in said tray.

Coin dispensing machines are normally provided with a chute having a delivery pocket which receives dispensed coins and from which the coins are scooped by hand. The delivery pocket of the chute may be placed within reach of the person receiving change from the coin dispensing machine and when so utilized admirably fulfills its intended function. However, when the coin dispensing machine is utilized to supply change for payroll envelopes or similar operations which are initiated and concluded by the operator, the chute with delivery pocket is unsuitable because of the difficulty of continuously scooping the coins from the delivery pocket. In such operations it is desirable that the coins be capable of being conveniently deposited within the hand of the operator for subsequent disposal so that the motions required by the operator are minimized.

The coin dispensing tray of this invention is designed to accomplish the purpose of providing a convenient means for depositing dispensed coins within the hand of the operator. In fulfillment of this function, the tray is provided with a movable bottom which is displaceable by simple pressure of the finger tips of the operator's outstretched open hand. Displacement of the movable bottom deposits coins in the palm of the operator's hand, thereby eliminating an additional step of scooping the coins from a pocket of a delivery chute. Preferably, the tray is adapted for removable attachment to the coin dispensing machine so that it may be interchanged with the aforementioned delivery pocket thereby offering the users of coin dispensing equipment alternate modes of coin delivery.

Accordingly, it is an object of this invention to provide a coin dispensing tray adapted for depositing dispensed coins into the palm of the hand.

It is a further object of this invention to provide a coin dispensing tray for removable attachment to the discharge of a coin dispensing machine and which is manually actuated by slight fingertip pressure from an outstretched hand.

It is also an object of this invention to provide a coin dispensing tray which insures removal of all deposited coins from the tray upon actuation.

It is another object of this invention to provide a manually actuated coin dispensing tray providing protection against injury to the actuating hand of an operator.

The foregoing and other objects and advantages of this invention will appear in the description which follows. In the description reference is made to the accompanying drawings which form a part hereof and in which there is shown by way of illustration a specific form in which this invention may be practiced. This form will be described in detail to enable those skilled in the art to practice this invention but it is to be understood that other embodiments of the invention may be used and that changes in the embodiment described may be made by those skilled in the art without departing from the true scope of the present invention. Consequently, the fol-

2

lowing detailed description is not to be taken in a limiting sense and the scope of the present invention is best defined by the appended claims.

In the drawings:

5 FIG. 1 is a view in perspective of the coin dispensing tray of this invention illustrated attached to a coin dispensing machine,

FIG. 2 is a view in vertical section taken in the plane represented by the line 2—2 of FIG. 1, and

FIG. 3 is a view in vertical section taken in the plane represented by the line 3—3 of FIG. 2, and

FIG. 4 is a view in vertical section similar to FIG. 3 showing the coin dispensing tray being actuated by the hand of an operator.

15 Referring to the drawings, the coin dispensing tray is adapted for attachment to a coin dispensing machine designated generally by the numeral 10 and which has a narrow inclined chute 11 into which coins are delivered. The chute 11 extends to a point exterior of the coin dispensing machine 10 through a discharge opening 12 provided in a side wall of the machine. An escutcheon plate 13 is mounted upon the side of the coin dispensing machine 10 and surrounds the discharge opening 12. It will be seen from FIG. 2 that the plate 13 is provided with an upturned bottom edge forming a mounting channel 14, and a mounting screw 15 is threadedly received through the plate 13 and in the side wall of the coin dispensing machine 10. Since the coin dispensing machine 10 including its coin release mechanism forms no part of the present invention, further details of construction have been omitted.

30 The coin dispensing tray includes a mounting plate 16 having a general configuration similar to that of the plate 13 and provided at its upper end with a slot 17 enlarged at its bottom to accommodate the head of the mounting screw 15, and provided at its lower edge with slots 18 which receive projections 19 extending from the plate 13. A coin entrance 20 is provided centrally of the mounting plate 16 to register with the discharge opening 12. A stationary member 21 is suitably bent to form a short leg 22 which is affixed to the mounting plate 16 by screws 23 to one side of the coin entrance 20, a rear wall portion 24 which projects from the mounting plate 16 and is normal thereto, and an end wall portion 25 extending from the outer edge of the rear wall portion 24 parallel to the mounting plate 16 and opposing the coin entrance 20. The rear wall portion 24 extends downwardly to a level below that of the bottom of the coin entrance 20 and terminates in a lower edge 26.

45 The rear wall portion 24 is provided with a projecting ear 27 at each side adjacent its upper edge, and a shaft 28 is journaled at each end through one of the ears 27 with its axis generally normal to the mounting plate 16. Similar ears 29 are provided at either side of a movable

50 member 30 and such ears are mounted upon extending ends of the shaft 28 to permit rotation of the movable member 30 about the shaft 28 and relative to the stationary member 21. The movable member 30 includes a back plate portion 31 which in the normal position of

60 the tray overlies the rear wall portion 24, and an arcuate tray bottom portion 32 extends from the back plate portion 31 beneath the lower edge 26 of the rear wall portion 24 and between the mounting plate 16 and end wall portion 25. The curvature of the tray bottom portion 32 is defined by an arc described by the lower edge 26 of the rear wall portion 24 as the tray bottom portion 32 is displaced rearwardly about the shaft 28. The lower edge 26 sweeps the inner coin supporting surface of the tray bottom portion 32 as the same is moved rearwardly and, although some clearance is desirable, the clearance between the lower edge 26 and the tray bottom portion 32 should not exceed the thickness of the thinnest

70

coin to be accommodated. The forward edge of the tray bottom portion 32 preferably rises to a level above that of the bottom of the coin entrance 20 and a stop lug 33 extends from the forward edge of the tray bottom portion 32 adjacent the mounting plate 16. The lower edge of the end wall portion 25 is preferably curved to conform with the configuration of the tray bottom portion 32.

A protecting shroud 34 extends from the top of the back plate portion 30 and overhangs the shaft 28. A spring 35 surrounds the shaft 28 and has one end biasing against the inner surface of the rear wall portion 24 and a second end biasing against the underside of the shroud 34 so that the movable member 30 is normally biased towards a coin receiving position in which the tray bottom portion 32 is disposed beneath the coin entrance 20. A coin deflection plate 36 is secured to the mounting plate 16 by screws 37 and the deflection plate 36 slopes from the bottom of the coin entrance 20 towards the tray bottom portion 32 to direct discharged coins toward the receptacle formed by the rear wall portion 24, the end wall portion 25 and the tray bottom portion 32.

Finger engageable means in the form of a plate 38 are mounted on the underside of the tray bottom portion 32. The plate 38 is provided with a gentle L-shape in which a major leg 39 is secured normal to and transverse of the tray bottom portion 32 and a minor leg 40 is disposed generally normal to and longitudinally of the tray bottom portion 32 and spaced from the mounting plate 16.

The coin dispensing tray is mounted upon the side of the coin dispensing machine 10 by initially placing the head of the mounting screw 15 through the enlarged hole portion of the slot 17 and then sliding the mounting plate 16 downwardly against the plate 13. In this position, the bottom of the mounting plate 16 rests within the mounting channel 14 and the screw 15 is disposed within the narrow portion of the slot 17. Tightening of the mounting screw 15 will then restrain the coin dispensing tray against the side of the coin dispensing machine 10. It is also to be noted that the projections 19 which fall within the slots 18 provided in the mounting plate 16 prevent lateral movement of the coin dispensing tray. When mounted, the coin entrance 20 provided in the mounting plate 16 registers with the discharge opening 12 of the machine 10 and the chute 11 of the machine projects through the coin entrance 20.

With the tray in position, the spring 35 will bias the movable member 30 so that the back panel portion 31 overlies the rear wall portion 24 and the tray bottom portion 32 is in position to receive coins. When coins are discharged from the machine 10 down the chute 11, they will be deposited in the tray upon the curved surface of the tray bottom portion 32, as shown in FIG. 3. The deflection plate 36 directs the coins generally towards the center of the tray and away from the immediate area adjacent the side wall of the machine 10. After a particular discharge of coins has been completed, the operator places the fingers of his open hand, with palm up, against the plate 38 and moves the movable member 30 including the tray bottom portion 32 rearwardly against the force of the spring 35. This action is illustrated in FIG. 4 which also shows coins deposited in this tray. Coins which have been deposited within the tray will be restrained by the rear wall portion 24 whose lower edge 26 sweeps the inner surface of the tray bottom portion 32 as the movable member 30 is moved rearwardly. The movable member 30 may be moved to a position in which the entire bottom of the tray will be effectively removed. The operator's hand, which has been employed to displace the tray bottom portion 32, will then be in a position to receive the coins as they fall from the tray. The stop lug 33 prevents the displacement of the movable member 30 beyond a position in which the bottom of the tray is removed by engaging the rear wall portion 24. Removal of the opera-

tor's hand permits the movable member 30 to return to its coin receiving position under the action of the spring 35.

The minor leg 40 of the finger plate 38 guards the operator's hand from abrasion or scratching on the surface of the machine 10 or the mounting plate 16 as the hand moves rearwardly. The deflection plate 36 by directing the deposited coins away from the machine 10, places them in a position in which they will fall into the palm of the hand rather than possibly slipping between the hand and the side of the machine 10.

It will be seen from the above description that the coin dispensing tray of this invention provides an efficient means for permitting the deposit of coins directly into the hand of an operator. The tray is fully detachable from the associated coin dispensing machine and provides positive assurance that coins deposited in the tray will be caused to fall into the operator's palm when the tray is actuated.

We claim:

1. A coin dispensing tray for attachment about the discharge opening of a coin dispensing machine, comprising: a mounting plate adapted for attachment to the coin dispensing machine and having a coin entrance adapted to register with said discharge opening; a rear wall member mounted upon said mounting plate and having a lower sweep edge; a shaft mounted by said rear wall member and having its axis generally normal to said mounting plate; a movable member mounted for rotation upon said shaft and including a displaceable tray bottom portion for receiving coins deposited in said tray and having a coin supporting surface cooperating with the sweep edge of said rear wall member; and finger engageable means on said tray bottom portion for displacing said movable member rearwardly causing said sweep edge to sweep the coin supporting surface of said tray bottom portion and thereby permitting coins to fall from said tray.

2. A coin dispensing tray for attachment about the discharge opening of a coin dispensing machine, comprising: a mounting plate adapted for removable attachment to the coin dispensing machine and having a coin entrance adapted to register with said discharge opening; a stationary member secured to said mounting plate and including a rear wall portion projecting from said mounting plate and provided with a lower sweep edge, and an end wall portion spaced from said mounting plate; a shaft mounted by said stationary member and having its axis generally normal to said mounting plate; a movable member including a back plate portion mounted for rotation upon said shaft and a tray bottom portion extending between said mounting plate and the end wall portion of said stationary member and having an inner surface defined by an arc described by the lower sweep edge of said rear wall portion as the movable member is rotated about said shaft; means biasing said back plate portion against said rear wall portion to position said tray bottom portion beneath said coin entrance for receiving discharged coins; and finger engageable means mounted on the underside of said tray bottom portion for displacing said movable member rearwardly against the action of the biasing means and thereby permitting coins to fall from said tray.

3. A coin dispensing tray for attachment about the discharge opening of a coin dispensing machine, comprising: a mounting plate adapted for removable attachment to the coin dispensing machine and having a coin entrance adapted to register with said discharge opening; a stationary member secured to said mounting plate and including a rear wall portion projecting from said mounting plate to one side of said coin entrance and provided with a lower sweep edge at a level below that of said coin entrance, and an end wall portion extending from the outer edge of said rear wall portion generally parallel with said mounting plate and opposing said coin entrance; a shaft mounted by said rear wall portion and having its axis generally normal to said mounting plate; a movable member including a back plate portion mounted for rotation adjacent its

upper edge upon said shaft, and a tray bottom portion extending from a lower edge of said back plate portion beneath said lower sweep edge and between said mounting plate and said end wall portion, said tray bottom portion having an inner surface defined by an arc described by the lower sweep edge of said rear wall portion as the movable member is rotated about said shaft, the forward edge of said tray bottom portion rising to a level above that of the bottom of said coin entrance; means biasing said back plate portion against said rear wall portion to position said tray bottom portion beneath said coin entrance for receiving discharged coins; and finger engageable means mounted on the underside of said tray bottom portion for displacing said movable member rearwardly against the action of the biasing means and thereby permitting coins to fall from said tray.

4. A coin dispensing tray for attachment about the discharge opening of a coin dispensing machine, comprising: a mounting plate adapted for removable attachment to the coin dispensing machine and having a coin entrance adapted to register with said discharge opening; a stationary member secured to said mounting plate and including a rear wall portion projecting from said mounting plate to one side of said coin entrance and provided with a lower

sweep edge, and an end wall portion generally parallel with said mounting plate and opposing said coin entrance; a shaft mounted by said rear wall portion and having its axis generally normal to said mounting plate; a movable member including a back plate portion mounted for rotation upon said shaft and a tray bottom portion extending between said mounting plate and the end wall portion of said stationary member and having an inner surface defined by an arc described by the lower sweep edge of said rear wall portion as the movable member is rotated about said shaft; a deflection plate sloping from the bottom of said coin entrance towards said tray bottom portion to direct discharged coins into the receptacle defined by said rear wall portion, said end wall portion and said tray bottom portion and away from said mounting plate; means biasing said back plate portion against said rear wall portion to position said tray bottom portion beneath said coin entrance for receiving discharged coins; and finger engageable means mounted on the underside of said tray bottom portion for displacing said movable member rearwardly against the action of the biasing means thereby permitting coins to fall from said tray, and including a finger guard portion spaced from said mounting plate.
